UNITED STATES PATENT OFFICE.

MAURICE NORVAL PRANGE, OF DETROIT, MICHIGAN.

PORTABLE SANDING, ABRADING, AND POLISHING MACHINE.

1,421,303.

Specification of Letters Patent. Patented June 27, 1922.

Application filed July 20, 1920. Serial No. 397,731.

To all whom it may concern:

Be it known that I, MAURICE N. PRANGE, a citizen of the United States, and a resident of Detroit, in the county of Wayne and State 5 of Michigan, have invented a new and Improved Portable Sanding, Abrading, and Polishing Machine, of which the following is a full, clear, and exact description.

The present invention relates to new and 10 useful improvements in surfacing machines, and it pertains more particularly to devices of this character especially adapted for surfacing floors, also for automobile bodies and furniture.

15 It is the primary object of the present invention to provide a plurality of surfacing elements, the operating face of which may be provided with any suitable element, such, for example, as sand-paper, brushes, 20 or the like.

It is a further object of the present invention to provide a means for simultaneously reciprocating said surfacing elements.

25 It is a further object of the invention to provide a device of this character which is capable of movement over the surface operated upon.

It is a further object of the invention to 30 provide a single power unit for operating said surfacing elements.

It is a still further object of the invention to mount the surfacing elements in such a manner as to reduce the friction of their reciprocal movement.

35 With the above and other objects in view, reference is had to the accompanying drawings, in which—

Figure 1 is a top plan view of a device 40 constructed in accordance with the present invention;

Fig. 2 is a sectional view thereof taken on the line 2—2 of Fig. 1;

Fig. 3 is a sectional view taken on the line 3—3 of Fig. 1;

45 Fig. 4 is a detail sectional view showing the manner of supporting the surfacing elements for reciprocal movement and taken on the line 4—4 of Fig. 2;

Fig. 5 is a detail top plan view of one of 50 the surfacing elements;

Fig. 6 is a side elevation thereof.

Referring more particularly to the drawings, the device comprises a frame 10 of rectangular form. This frame 10 is provided with a pair of spaced braces 11 in the form of upstanding webs which extend

transversely of the frame as shown in Fig. 1. The frame 10 is supported upon rollers or caster wheels 12, which form the means for rendering the machine portable over the 60 surface operated upon.

Suitably mounted on the frame is a motor 13, preferably of the electric type, and the armature shaft of said motor has one of its ends projected beyond the casing and carries a bevel gear 14. Mounted on the frame and secured to the platform 15 thereof, is a plurality of bearings 16, said bearings being secured in place by means of screw bolts or the like 17. As shown in Fig. 1, the 70 platform 15 is secured within the frame 10 by means of clips or brackets 18, and bolts 19, the clips or brackets 18 being carried by the platform 15 and resting on the upper edge of the frame as indicated at 20 in said 75 figure.

Extending transversely of the machine and mounted in the bearings 16, is a shaft 21, and said shaft 21 is provided with a plurality of bevel gears 22, as best seen in Fig. 80 1. The reference character 23 designates a plate secured to the platform 15 by means of a bolt 24, and said plate 23 has a vertically projecting arm 25. This arm 25 is provided with two right-angular extensions 26 and 85 27, which lie in a horizontal plane and mounted for rotation in said right-angular extensions 26 and 27 is a vertical shaft 28. Secured to the vertical shaft 28 in such a manner as to rotate therewith is a bevel gear 90 29, and said bevel gear 29 is adapted to mesh with the bevel gear 14 heretofore mentioned on the armature shaft of the motor 13. Secured to the lower end of the vertical shaft 28 is a bevel gear 30, and said bevel gear 30 95 is adapted to mesh with the bevel gear on the transversely extending shaft 21 in order to rotate said shaft.

Mounted in the transverse braces 11, are shafts 31, said shafts being mounted at each 100 end in roller bearings 32 carried by said transverse braces. Secured to each of the shafts 31 by means of a set screw or the like 33, is a cam member 34, said cam member being channeled as indicated at 35. 105 Each of the shafts 31 carries a bevel gear 36 secured thereto by means of a key or the like 37, and each of these bevel gears 36 is so positioned as to lie adjacent one of the bevel gears 22 and in mesh therewith in such 110 a manner that as the shaft 21 is rotated, each of the bevel gears 36 will likewise be driven

to rotate its respective shaft 31, thus driving its respective cam member 34. By this mechanism it will be apparent that as the motor is operated through the medium of 5 the bevel gear 14 meshing with the bevel gear 29, to drive the vertical shaft 28, the bevel gear 30 will be rotated, and through the medium of the gear with which it meshes, will drive the shaft 21. Upon rotation of the shaft 21, each of the bevel gears 22 acts to drive its respective gear 36, thereby providing for a rotary movement of the several cams 34.

The platform 15 is cut out or channeled as indicated at 40, and lying within each of said channels 40 are the opposed half sections 41 of a ball race, each of said half sections 41 being secured to the under side of the platform 15 by means of bolts, rivets 20 or the like 42. The reference character 43 designates the several polishing elements, and secured to opposite sides of each of the polishing elements are halves 44 of ball races, which halves are adapted to lie opposite the halves 41 to form complete raceways for the reception of the anti-friction balls 45. By this mechanism, it will be seen that the several polishing elements are suspended beneath the platform 15.

30 As best shown in Figs. 5 and 6, each of the polishing elements 43 is cut out as indicated by the reference character 50, and closing said cut-out portion is an angle iron 51, one end of which is right-angularly disposed with respect to the body portion as indicated at 52. This angle iron is secured in place by means of bolts or screws 53 over the cut-out portion 50 of each of the polishing elements. As shown in Fig. 2, a plurality of wedges 54 are adapted to pass through the space in the cut-out portion 50 between the angle iron 51 and the polishing element 43, to secure the abrading material 55 in place, said abrading material being shown in the present instance as sand paper. In order to prevent displacement of the several wedges 54, longitudinal keys 56 are passed through cut-out portions 57 in said wedges.

50 Each of the polishing elements 43 is adapted to be secured to a reciprocating member 60, said polishing elements being fastened to the reciprocating element 60 by means of a bolt 61, which passes through an opening 62 in the right-angular extension 52 of the plate or angle iron 51. Mounted centrally of the ends of the reciprocating member 60, is a bolt 62', and said bolt 62' forms the means for securing a rotatable

dog 63 to the reciprocating member, said 60 dog 63 lying within the channel 35 of its respective cam member 34, it being understood that there is one reciprocating member 60 for each of the cam members 34. These dogs 63 each comprises a disk 64, 65 which disk is rotatably mounted on anti-friction balls or rollers 65.

From the above description it will be apparent that as each of the cams 34 is rotated as heretofore described, the channel 70 35 thereof will serve to reciprocate its respective dog 63, and will thereby operate its respective member 60. As the member 60 is reciprocated, it will be seen that the abrading surface carried thereby will be reciprocated rapidly over the surface treated, thereby smoothing said surface. It will further be apparent that owing to the supporting wheels or casters 12, the device is readily movable over the surface to be treated in order that the entire surface may be covered by the machine.

What is claimed is:

1. A device of the character described comprising a frame, a platform immovably carried by said frame, said platform having its under surface provided with a plurality of channels, guides mounted in each of said channels, an abrading element mounted in each of said channels and supported by said guides, a vertically-extending member carried by each of said abrading elements and projecting through an opening in the platform, a plurality of cam wheels adapted for engagement with each of the vertically-extending members whereby the abrading elements are reciprocated upon rotation of the cam wheels, and means for driving said cam wheels in unison, as and for the purpose set forth.

2. A device of the character described comprising a frame, a platform carried thereby, a plurality of abrading elements reciprocatively mounted in said platform, a plurality of parallel flanges projecting from the upper face of said platform, a plurality of cam wheels mounted between said flanges, a shaft for each of said cam wheels, a gear carried by each of said shafts, a shaft extending parallel to said flanges and 110 provided with a plurality of gears adapted for single engagement with the gears of the cam wheels, and means for driving said last-mentioned shaft to rotate the cam wheels and impart reciprocating movement to the 115 abrading elements.

MAURICE NORVAL PRANGE.
